UNITED STATES PATENT OFFICE.

CHARLES A. L. TOTTEN, OF MILFORD, CONNECTICUT.

DESIGN FOR A BUTTON OR SIMILAR ARTICLE.

SPECIFICATION forming part of Design No. 36,255, dated March 31, 1903.

Application filed February 19, 1903. Serial No. 144,168. Term of patent 14 years.

To all whom it may concern:

Be it known that I, CHARLES A. L. TOTTEN, of Milford, in the county of New Haven and State of Connecticut, have invented and produced a new, original, and ornamental Design for a Button or Similar Article; and I do hereby declare the following, when taken in connection with the accompanying drawings and the letters of reference marked thereon, to be a full, clear, and exact description of the same, and which said drawings constitute part of this specification, and represent, in—

Figure 1, a full-size top view of a lapel-button embodying the same; Fig. 2, a sectional view thereof. Fig. 3 shows the design upon the reverse of the button.

As herein shown, my design consists of a circular head A, shank B, and base C. The ornamentation on the face of the head consists, first, of a five-pointed "constellation" composed of thirteen smaller five-pointed stars D, all concentrically arranged so as to face outward from the interior or central one, the seven interior to the exterior five being arranged in a circle; second, beyond the blank

space occupied by the central star cluster there is a "glory" or circle of rays E, and, third, these rays are seen to break the surrounding circular cloud F into thirteen sections, each and all shaded dark upon the outside and shown as rolling back, while the glory, itself indicated by a series of radiating lines, breaks through and beyond, as indicated by the circular milled edge G, which finishes the artistic face part of the design. 35

Upon the base C of the button appears an eye H in a triangle J, surrounded by rays K, forming a glory to complete the design.

Having fully described my invention, what I claim as new, and desire to secure by Letters 40 Patent, is—

The ornamental design for a button or similar article, as herein shown and described.

In testimony whereof I have signed this specification in the presence of two subscribing witnesses. 45

C. A. L. TOTTEN.
